UNITED STATES PATENT OFFICE

RICHARD A. BURNETT, OF WILMINGTON, NORTH CAROLINA

ROAD-SMOOTHING MACHINE

Application filed September 21, 1927. Serial No. 221,025.

My invention relates to a road smoothing machine, and a method and means of imparting a smooth surface to all bitulithic, asphalt or similar pavements.

5 An object of my invention is to provide a road smoothing machine which will shave off the high places in a road and will deposit the shaved-off material in the low places in the road and will smooth the surface of the 10 roadway.

Some of the objects of my invention having been stated, other objects will appear as the description proceeds when taken in connection with the accompanying drawings in 15 which—

Figure 1 is a perspective view of my road smoothing machine;

Figure 2 is a plan view of a slight modification of my machine;

20 Figure 3 is a sectional view taken along the line 3—3 in Figure 2.

Figure 4 is an enlarged detailed view of the means for raising the machine when it is desired to turn the same.

25 Referring more particularly to the drawings the numeral 1 indicates the runners of my machine, on which there is adapted to be secured additional runner members 7.

Running from one of the members 1 to the 30 other member 1 is a cross piece 2, which is disposed at the front end of the machine and at the rear end of the machine there is the cross member 3 which is adapted to be placed in an inclined position for purposes

35 of smoothing the road. Disposed rearwardly of cross member 2 is the angularly disposed member 5, and rearwardly of this member 5 is another angularly disposed member 6, both of these members being at approxi-

40 mately sixty-five degrees with relation to the longitudinally disposed runners 1. All of these cross members have secured to their front surfaces the steel blades 8. These steel blades 8 have vertically disposed slots 9 therein, and penetrating these slots and the 45 slots 20 in the cross members are the bolts 21 having the nuts 22 thereon, and by reason of this arrangement the vertical position of the blades 8 may be adjusted with relation 50 to the cross members. Secured to the cross

members are the upwardly and forwardly projecting members 23 through which the bolts 24 are adapted to be inserted, said bolts having the nuts 10 thereon. These bolts are secured in the lugs 24^a on the steel blades 8 and after the nuts 22 have been loosened, the blades 8 may be adjusted by means of the nut 10 and the bolt 24. The cross-members are secured to the runners by means of the members 25. The members 12 are secured to the top portions of the runners 1 on which wheels may be placed when it is desired to transport the machine from place to place when not in use for road smoothing purposes.

55 Secured to the cross member 5 is a steel plate 26, and penetrating this steel plate 26 is the screw member 11 which has mounted on the lower end thereof, the member 27, the purpose of this mechanism being that when such screw member is placed in the position 60 shown in Figure 4, that the machine will be raised from the pavement so that it may be turned easily. Secured to this steel plate 26 and projecting rearwardly thereof and being secured to the rear portion of the members 1 are the brace members 4.

65 A hole 13 is cut in the rearmost portion of the first named angularly disposed blade 8 and a hole is also cut through the cross member 5 in order to allow surplus material 70 to fall through this hole to be engaged by the blade secured to the cross member 6.

In the Figure 2 I have shown in addition to the structure described in Figure 1, members 30, 31, 32 and 33, which are placed on top of the runners 1 for the purpose of 75 strengthening the structure and also for carrying weights such as sand bags in order to give the best working results, and in this modification, the rear end of steel plate 26 80 is secured on top of the member 31, otherwise, the structure is the same as the structure shown in Figure 1 with the exception that the cross member 3 has the steel blade 34 secured thereon in the same manner as 85 the steel blades 8 are secured to the other members. In using my machine I find it best to use the same during the summer months 90 when the bitulithic, asphalt or similar pavement is in soft condition, and when such is 95 100

the case, the blades will scrape off the high places in the road, the front blade which is mounted on the cross member 2 being set at a higher elevation than the succeeding blade, that the shaved-off portions will strike the blade on the cross member 5 which will deposit the shaved-off portion in the low places in the road and any surplus material will fall through the hole 13 and be caught by the blade on the cross member 6, and the cross member 3, being set at an inclined position, will smooth and polish the surface of the road and have a tendency to pack the deposited material in the low places.

13 I have found that best results can be obtained by applying to the pavement to be treated a coating of asphalt with other material and then applying a coating of gravel or similar material. This coating of asphalt will soften the surface of the road and will also act as a binder for the gravel and shaved-off portions which is deposited in the low places in the road. The shaved-off portions and the gravel and the asphalt will be mixed 25 with each other thoroughly by the action of the blades on the cross members 5 and 6 and the large gravel and shaved-off portion will be deposited in the deeper holes in the road and the smaller portion will be deposited 30 in the shallower holes in the roadway.

In the drawings and specification I have set forth a preferred embodiment of my invention, and although specific terms are employed, they are used in a generic and descriptive sense only and not for purposes of limitation, but the scope of the invention being set forth in the appended claim.

I claim:

In a road smoothing machine, comprising longitudinally disposed members, steel runners secured on the bottom of said members, a front cross-beam extending from one runner to the other, a rear cross-beam extending from one runner to the other, an angularly disposed cross-beam in the rear of the first cross-beam, a second angularly disposed cross-beam disposed in the rear of the first angularly disposed cross-beam, steel cutting blades secured on the cross-beams, vertically disposed slots in the cross-beams, vertically disposed slots in the steel blades, bolts penetrating the slots to adjustably hold the blades with relation to the cross-beams, lugs secured on the upper surface of the cross-beams, bolts secured to the blades and penetrating the lugs and a nut on the top of each of the lugs threadably engaging the bolts.

In testimony whereof I affix my signature.

RICHARD A. BURNETT.
